WERNER CHRISTIAN LASSEN HAUBROE, OF COPENHAGEN, DENMARK.

DRUM-SHAPED CARTRIDGE MAGAZINE FOR MACHINE GUNS OR THE LIKE.

Application filed September 3, 1924, Serial No. 735,548, and in France October 7, 1923.

The present invention relates to a drum-shaped cartridge magazine for machine guns or the like, by which the cartridges are fed forward along a spiral path. It has been attempted, heretofore, to use such magazines, but the heretofore constructed magazines of this kind have proved inefficient, as it has not been possible to attain a uniform forward motion of the cartridge, especially when the magazine is arranged to take a large number of cartridges and, especially, during the first portion of the forward motion of the cartridges.

The use of magazines for a large number of cartridges, for instance 100 pieces, is necessary especially in case of machine guns for flying machines, as the period during which firing may be continued against another flying machine or against troops either in motion or in a trench or concentrated at certain points is very much limited, so that time must be utilized as much as possible, and does not permit the magazine to be changed during firing. The only useful shape of magazine for a large number of cartridges during such or similar conditions is the drum-shaped one, as such a magazine occupies a minimum of space, and offers a minimum surface for the action of wind. Flat, box-shaped magazine, if they are to take for instance 100 cartridges, would be far too long and offer too large a surface for action of wind, and will therefore be very difficult to place in position, and they will prevent the free adjustment of the gun for firing or during the same, while the gun ought to have the largest possible freedom of adjustment, in order that the gun may be directed against and maintained directed against the object, no matter where the latter is situated, and how it alters its position relatively to the flying machine, on which the magazine gun is carried.

The drum-shaped magazine must also be arranged in such a manner that the cartridges may be fed forward continuously, no matter what elevation the machine gun is given during firing.

All these requirements are fully filled by the cartridge magazine forming the object of the present invention.

On the drawing,

Fig. 1 shows the cartridge magazine, viewed from the side facing the gun,

Fig. 2 the same in front view,

Fig. 3 a section along the line III—III of Fig. 2,

Fig. 4 a section along the line IV—IV of Fig. 1,

Fig. 5 a vertical longitudinal section of 60 the feeding lever for the cartridges,

Fig. 6 a horizontal section of the same, and

Fig. 7 the feeding lever viewed from its free end.

65

The cartridge magazine consists of a conical casing 1, the conicity of which is adjusted to suit the kind and size of the cartridges the magazine is intended to hold. The house has on one side a tangentially disposed outlet spout 2 adapted to be attached in the spout on the lock frame of the machine gun by way of which the cartridges are introduced into the machine gun. The casing is also fitted with a handle bar 3. 75

To the bottom of the casing 1 a spiral rail 4, Figs. 3 and 4, is attached, and a similar rail 5, Fig. 3, is attached to the top plate of the casing, so that two spiral tracks 6 and 7 are provided inside of the casing adapted 80 to guide the wide and the narrow end of the cartridges, respectively.

Centrally in the casing a shaft is journaled consisting of two pieces 8 and 9, one of which 8 supports a feeding lever 10, 11, 12, while the other piece passes through a spring house 13 attached to the top plate of the casing. In the spring house there is provided a powerful spiral spring 14, one end of which is attached to the wall of the 90 house 13, while its other end is connected to the shaft portion 9. The two shaft portions 8 and 9 are interconnected in such a manner that they revolve together, for instance by means of a lug 15 on the shaft part 9, the 95 said lug engaging a notch 16 in the shaft part 8, Figs. 3 and 5. The said shaft part is fitted, at the end journaled in the bottom of the casing 1, with an incision 17 for a suitable key by means of which the shaft 8, 100 9 may be turned, when the spiral spring 14 is to be tightened.

The feeding lever, Figs. 5 and 6, consists of three tubes 10, 11 and 12 adapted to telescope inside of one another. The tube 10 is 105 made in one with or firmly connected to the shaft part 8 and has, at one end, a screw-hole for a stopping screw 18, Fig. 6, one end of which engages a longitudinal slot 19 in the tube 11, whereby the longitudinal 110

motion of this tube inside of the tube 10 is limited.

The tube 12 has on one side, at its end facing the shaft part 8, a projecting lug 20 engaging a longitudinal slot 21 in the wall of the tube 11 and, thereby, preventing the tube 12 from being turned relatively to the tube 11, the rotation of the latter relatively to the tube 10 being prevented by the 10 stopping screw 18. At the end facing the wall of the casing 1, the tube 12 is fitted with an arm 22, which is parallel to the sloping wall of the casing 1 and supports, at its bottom end, a roll 23 running in the 15 track 6.

At the end facing away from the tube 11 the tube 10 is closed by means of a threaded cap 24, the bottom of which serves as bearing surface for the head of a bolt 25, 20 while a helical spring 26 encircles the bolt and presses against the other side of its head. The other end of this helical spring rests against an end bottom 33 in the tube 12, in such a manner that the helical spring 25 after having been compressed tends to move the tubes 11 and 12 out towards the wall of the casing 1 and, thereby, maintains the roll 33 pressed against the outer wall in the track 6.

30 27 is a pivoted stopping lever preventing the cartridges held in the magazine from being pressed out of the spout of the magazine, when the latter is not attached to the gun. This stopping lever is a double-armed lever, and the end of the same facing the orifice of the magazine is fitted with a tooth 29 with two sloping surfaces 30 and 31. The stopping lever 27 is actuated by a helical spring 28 tending to turn the stopping 35 lever in such a manner that the end of the same facing the orifice of the magazine enters the latter, see Fig. 4. The rotation of the stopping lever caused by the spring is limited by the other end thereof resting 40 against the wall of the casing 1.

When the magazine is to be filled with cartridges, the spiral spring 14 is moved by means of a key, which as mentioned above is inserted into the incision 17 of the shaft 50 piece 8, and by means of which the shaft 8, 9 is rotated, but only so much that the cartridges inserted are constantly pressed against each other, and the innermost cartridge against the lever 22. The cartridges 55 are inserted one by one through the spout 2, the feeding lever being gradually turned inwardly in the casing 1 by means of the key, the length of the said lever being gradually reduced during this rotation in consequence 60 of the roll 23 travelling along the spiral track 6. During this insertion of the cartridges the stopping lever 27 swings in and out, while the cartridges slide on the two sloping surfaces 30 and 31 of the tooth 29 65 and, after the insertion the wide end of the

cartridges is guided in the track 6 and the narrow end in the track 7, while the spiral spring 14 is gradually becoming wound by the rotation of the shaft 8, 9. The stopping lever 27 prevents constantly the cartridges inserted in the magazine from being pressed out of the same by the pressure of the spiral spring 14, the end face 32 of the said lever resting against the outer cartridge in the magazine. 75

When the filled magazine is placed on the supply spout of the gun, the stopping lever 27 is released automatically in similar manner as in case of ordinary box magazines, so that the individual cartridges may 80 freely move past the stopping lever from the magazine into the gun by the pressure exerted by the spiral spring 14 on the feeding lever 10, 11, 12, whereby this lever is moved forward along the spiral tracks 6 and 7, 85 while its arm 22 during the entire forward motion rests against the innermost cartridge in the magazine, the feeding lever proper being gradually rendered longer by the pressure of the helical spring 26. 90

When the magazine is removed from the gun, and cartridges are still left in the same, then the stopping lever 27 enters at once in front of the outermost cartridge, the tooth 29 of the stopping lever entering between 95 the said cartridge and the one resting in the spout of the lock frame of the gun, whereby it prevents the cartridges left in the magazine from dropping out of the magazine. 100

In the bottom of the casing 1 holes 34 are drilled at various points opposite the track 6, each hole being marked with a number corresponding to the number of the cartridge resting opposite the hole concerned, when the magazine is full. Hereby it becomes practicable to ascertain how many cartridges are left in the magazine, when firing is stopped, before the magazine is empty. 105 110

Having thus described my invention, what I claim is:—

1. A cartridge magazine for machine guns, comprising, in combination, a drum-shaped housing, means forming a spiral path within 115 said housing adapted to receive a plurality of cartridges, a shaft mounted for rotation within the housing, a tubular telescoping lever carried by said shaft and bodily rotatable therewith, resilient means within said lever for urging the same toward its extended position, a roller carried by said lever and adapted to travel in said spiral path, a spiral spring for rotating said shaft thereby to cause said roller to travel from the inner to 120 the outer end of the spiral path, and means for winding said spring and carrying the roller from the outer toward the inner end of said path. 125

2. A cartridge magazine for machine guns, 130

comprising, in combination, a drum-shaped housing, means forming a spiral path within said housing adapted to receive a plurality of cartridges, a shaft mounted for rotation within the housing, a tubular telescoping lever carried by said shaft and bodily rotatable therewith, resilient means within said lever for urging the same toward its extended position, a roller carried by said lever and adapted to travel in said spiral path, a spiral spring for rotating said shaft thereby to cause said roller to travel from the inner toward the outer end of the spiral path, means for winding said spring and carrying the roller from the outer toward the inner end of said path, a spring actuated pivoted lever adapted normally to obstruct the outer end of said path and prevent the escape of cartridges therefrom, said lever being automatically swung on its pivot when the magazine is attached to a gun thereby to permit the passage of cartridges from the magazine into said gun.

3. A cartridge magazine for machine guns, comprising, in combination, a drum-shaped housing, means forming a spiral path within said housing adapted to receive a plurality of cartridges, a shaft mounted for rotation within the housing; a tubular telescoping lever carried by said shaft and bodily rotatable therewith, resilient means within said lever for urging the same toward its extended position, an arm carried by said lever at its outer end, said arm being disposed at an angle to the lever, a roller carried by said arm and adapted to travel in said spiral path, a spiral spring for rotating said shaft thereby to cause said roller to travel from the inner toward the outer end of the spiral path, and means for winding said spring and causing the roller to travel from the outer toward the inner end of said path.

In testimony whereof I have signed my name to this specification.

WERNER CHRISTIAN LASSEN HAUBROE.
